UNITED STATES PATENT OFFICE.

JOHN PLATT, OF HARROW, ENGLAND, AND WILLIAM PLATT AND HENRY PLATT, OF ROUBAIX, FRANCE.

DRUM OR CYLINDER OF CARDING-ENGINES AND THE LIKE.

1,337,470.

Specification of Letters Patent. Patented Apr. 20, 1920.

Application filed February 11, 1920. Serial No. 357,834.

To all whom it may concern:

Be it known that we, JOHN PLATT, a subject of the King of Great Britain, residing at Byron Works, Bouverie Road, Harrow, 5 in the county of Middlesex, England, WILLIAM PLATT and HENRY PLATT, both subjects of the King of Great Britain, residing at 108 Rue de la Fontaine, Roubaix, in the Republic of France, have invented certain 10 new and useful Improvements in or Relating to the Drums or Cylinders of Carding-Engines and the like, of which the following is a specification.

This invention relates to the drums or cylinders of carding engines, burring apparatus, waste openers and the like, (hereinafter referred to as carding engines), the chief object being to reduce the cost of manufacturing and clothing the said drums 20 or cylinders and to enable the same to be clothed with rapidity.

As is well understood, the clothing of the said drums or cylinders with saw toothed or serrated metal wires or strips is usually 25 effected by forming a spiral groove in the periphery of the drum into which the saw toothed or serrated metal strip or wire is inserted and secured in place. This method, however, is extremely costly besides necessi- 30 tating the use of metal drums or cylinders.

According to the present invention the peripheral surface of the drum or cylinder, which may be composed of wood, metal or other suitable material, is prepared for the 35 reception of the clothing by lapping or spirally winding thereon a flat strip or band of metal of any desired width, one or both edges of the said strip being upturned or flanged so as to accommodate and to serve

40 to retain in position between the edges or flanges which are thus provided, the saw toothed wires or strips which form the clothing. Owing to this arrangement the usual operation of grooving the peripheral surface of the drum for the purpose of accommodating the saw toothed wires is rendered unnecessary, as the upturned edges or flanges of the metal band form a continuous spiral surface around the drum and act as 45 supports for any desired number of saw toothed wires. The band is fixed to the drum by screws, nails or other suitable attaching means.

In order that the said invention may be 50 clearly understood and readily carried into

effect, the same will now be described more fully with reference to the accompanying drawing which shows the invention more or less diagrammatically, and in which:—

Figure 1 is a sectional end view of one of 60 the aforesaid metal strips or bands provided with a single upturned edge or flange, and,

Fig. 2 is a similar view showing a modified form of strip having two upturned 65 edges or flanges.

Fig. 3 is a cross sectional end view of the saw toothed wire which constitutes the card clothing.

Fig. 4 is a perspective view of part of a 70 carding engine drum or cylinder showing the aforesaid metal band in the process of being lapped or spirally wound thereon and,

Fig. 5 shows a complete drum or cylinder 75 after its peripheral surface has been prepared in this manner for the reception of the card clothing.

Fig. 6 is a view corresponding to Fig. 4 but showing the metal band and the toothed wire being applied simultaneously from different sources of supply to the peripheral 80 surface of the drum or cylinder, and,

Fig. 7 is an end view of a drum or cylinder to which there is being applied a band carrying a suitable number of saw toothed 85 wires, the combined band and saw toothed wires being wound simultaneously upon the drum or cylinder from a common source of supply.

Fig. 8 is a part sectional view of the drum 90 or cylinder on an enlarged scale showing the band and the saw toothed wires applied thereto.

Fig. 9 is an elevation of a pair of carding rollers constructed in accordance with the 95 present invention and in which the rollers are provided at their ends with circumferential metal bands which act as distance pieces for insuring the correct positioning of the rollers and of the card clothing carried 100 thereby relatively to each other.

A is the drum or cylinder; B is the aforesaid strip or band and C is the saw toothed wire which constitutes the card clothing. In Figs. 4 to 9 the strip or band B is provided 105 with a single upturned flange (Fig. 1) this being the preferred form. As shown at Fig. 4, the strip or band B may first be lapped spirally around the drum A and secured in place in any suitable manner, thus produc- 110

ing a drum as shown at Fig. 5 which is ready for the reception of the saw toothed wires C which are to form the clothing of the drum, the wires C being thereafter 5 lapped on between the upturned edges of the strip or band B. Alternatively the band B and a suitable number of saw toothed wires may be lapped on simultaneously as shown at Fig. 6, or as shown at Fig. 7 the band 10 may be prepared initially with the requisite number of saw toothed wires accommodated therein or attached thereto and the composite band may be applied to the drum in a single winding operation as shown at Fig. 15 7. At the beginning and at the end of the lapping operation the ends of the strip or band C as also the saw toothed wires c are suitably cut or tapered to conform to the shape of the drum A.

20 The application of the clothing and of the supports therefor can thus be effected expeditiously and cheaply and any number of saw toothed wires can be employed and packed as closely as desired in the space between the upturned flanges of the metal band. The aforesaid saw toothed wires may be of any suitable or usual cross section and may be provided with a suitable foot or flange of sufficient width to act as a 25 distance piece and to afford the desired support for the saw toothed wires.

At the present time considerable difficulty is experienced in correctly locating the co-operating pairs of drums or cylinders at the 35 requisite distance apart for the proper treatment of the wool or other material to be dealt with, the adjusting operation being one of great delicacy and requiring the exercise of considerable skill owing to the fact 40 that the card clothing is liable to be damaged or destroyed should the rollers be brought into too close proximity to each other. With the object of insuring the accurate spacing apart of the co-operating 45 pairs of rollers in a simple and expeditious manner the arrangement shown at Fig. 9 may be adopted. To this end the swift rollers a and the working rollers a' are provided at their ends with circumferential 50 metal bands a², a² and a³, a³ respectively, the thickness of which is slightly greater than the height of the card clothing. Owing to this arrangement and when the swift and working rollers are mounted in position, the bands a², a² and a³, a³ contact with each 55 other and thus insure that the card clothing is correctly spaced apart.

What we claim and desire to secure by Letters Patent of the United States is:—

60 1. A method of clothing the drums or cylinders of carding engines which consist in

lapping or spirally winding upon the peripheral surface thereof, a flat strip or band having an upturned edge or edges, and card clothing, said card clothing being supported 65 upon the strip or band and between the upturned edges thereof.

2. A method of clothing the drums or cylinders of carding engines which consists in lapping or spirally winding upon the peripheral surface thereof a flat strip or band having an upturned edge or edges, said strip or band carrying initially the saw toothed wires constituting the card clothing so that the supporting strip or band and the card 75 clothing are applied in a single operation to the drum or cylinder.

3. A drum or cylinder for a carding engine having a metal strip applied thereto which has an upturned flange or flanges 80 which provide applied grooves upon the peripheral surface thereof and saw-toothed wires or strips supported within said grooves constituting the card clothing.

4. A drum or cylinder for a carding engine comprising a flanged metal strip which is applied in such manner to the drum or cylinder as to provide applied grooves upon the peripheral surface thereof, in combination with toothed or serrated wires or strips 90 accommodated therein, constituting the card clothing.

5. A drum or cylinder for a carding engine having a metal strip applied thereto which has an upturned flange or flanges 95 which provide applied grooves upon the peripheral surface thereof for accommodating and supporting the saw toothed wires or strips constituting the card clothing, the ends of said drum or cylinder being provided with circumferential bands which act, when the rollers are assembled in position in the machine, as distance pieces for determining the space or gap between each pair of co-acting rollers.

100 6. A drum or cylinder for a carding engine comprising a flanged metal strip which is applied in such manner to the drum or cylinder as to provide applied grooves upon the peripheral surface thereof, in combination with toothed or serrated wires or strips 110 accommodated therein, the whole forming a new type of toothed or serrated card clothing, the ends of said drum or cylinder being provided with circumferential bands which 115 act, when the rollers are assembled in position in the machine, as distance pieces for determining the space or gap between each pair of co-acting rollers.
